UNITED STATES PATENT OFFICE.

ALEXANDER P. GROSS; OF SAN FRANCISCO, CALIFORNIA.

HARNESS-COUPING.

SPECIFICATION forming part of Letters Patent No. 274,487, dated March 27, 1883.

Application filed December 6, 1882. (No model.)

To all whom it may concern:

Be it known that I, ALEXANDER P. GROSS, of San Francisco, in the county of San Francisco and State of California, have invented 5 certain new and useful Improvements in Harness-Couplings; and I do hereby declare the following to be a full, clear, and exact description of the invention, such as will enable others skilled in the art to which it appertains to 10 make and use the same, reference being had to the accompanying drawings, and to letters of reference marked thereon, which form a part of this specification.

My invention relates to an improvement in 15 harness-couplings, the object of the same being to provide a device of this character which will combine simplicity, neatness, and economy of construction with durability and efficiency in use; and with these ends in view my 20 invention consists in certain details in construction and combinations of parts, as will be more fully explained, and pointed out in the claims.

This improvement is adapted for use as a 25 whiffletree-hook, for a coupling between the neck-yoke and pole, for a neck-yoke hook, and for other vehicle or harness-couplings; but for the sake of convenience I will describe my improvement in connection with whiffletries.

30 In the accompanying drawings, Figure 1 is a longitudinal sectional view, showing my improvement. Fig. 2 is a transverse sectional view through the line *x x* of Fig. 1, and Fig. 3 is a view in perspective of the ferrule.

35 A represents the whiffletree, to the opposite ends of which are rigidly secured the ferrules B. These ferrules are made of metal, and each is provided with the outwardly-extending collar or abutment *a*, and with the flange *b*, which 40 latter is situated between the collar *a* and the outer end of the ferrule. Each flange *b* is cut away or slotted, as shown at *c*, to enable the thimble D to be moved into position. This thimble can be made of any suitable metal, 45 ornamental or not, as desired, and is provided with the ring or loop E, to which the rear end of the trace can be rigidly secured. This thimble D is adapted to be removed from the whiffletree with the trace, and my main object 50 is to provide a coupling that can be manufactured at a small initial cost, and that can be

coupled and uncoupled in a comparatively short space of time. The thimble D is adapted to fit snugly on the ferrule B, and is enlarged at its larger or open end to enable it to pass 55 over the flange *b*. This thimble is provided at this enlarged portion with an inwardly-projecting lug, *d*, adapted, when the parts are together and adjusted, to hold the thimble in position on the ferrule. This lug *d* is of size 60 sufficient to readily pass through the slot *c*, and when it is desired to place the parts together the thimble is placed on the ferrule and turned thereon until the lug passes through the slot. The thimble is then turned slightly, 65 which movement locks the parts together.

F F are rubber or other suitable elastic gaskets, introduced, respectively, between the end *f* of the thimble and the collar or abutment *a* of the ferrule, and in the space between 70 the ferrule and the end of the thimble, and hold the said thimble on the ferrule without movement.

When it is desired to adjust the parts, the thimble is placed on the ferrule and turned 75 until the lug *d* enters the slot *c*. Pressure is then exerted on the end of the thimble, which compresses the rubber gaskets and enables the lug *d* to pass beyond the flange *b*. The thimble is then given a part turn and released. 80 After the thimble is released the rubber packing or gaskets press the thimble outward until the lug *d* bears against the flange *b* and holds the parts against displacement by frictional contact. To uncouple the parts it is 85 simply necessary to turn the thimble until the lug registers with the slot, when the rubber gaskets expand and force the thimble outward. It is then removed with the traces, and can be again coupled in the same manner when desired. 90

This invention, as before stated, can be applied to the ends of neck-yokes, can be employed for securing the neck-yoke to the carriage-pole, and in other places on a vehicle or harness where a similar coupling is necessary. 95

My invention is simple in construction, is of few parts, is durable and effective in use, and can be manufactured at a small initial cost.

Having fully described my invention, what I 100 claim as new, and desire to secure by Letters Patent, is—

1. The combination, with a ferrule provided with a collar or abutment, of a thimble adapted to be removably secured on the ferrule, the said thimble being provided with a ring or loop, by means of which it is secured to the harness, and a rubber gasket or gaskets interposed at one or more points between the thimble and ferrule, and adapted to operate as described.
- 10 2. The combination, with the ferrule provided with a collar or abutment, and a flange, the latter having a slot therein for the pas-

sage of the thimble, of the thimble adapted to snugly fit the ferrule, and provided with an inwardly-projecting lug, and one or more rubber gaskets interposed between the thimble and ferrule and adapted to operate as described.

In testimony that I claim the foregoing I have hereunto set my hand this 22d day of November, 1882.

ALEXANDER P. GROSS.
